US00D785493S

(12) **United States Design Patent** (10) **Patent No.:** **US D785,493 S**
(45) **Date of Patent:** **** May 2, 2017**

(54) **JEWEL DESIGN**

(71) Applicant: **FIRESTAR DIAMOND, INC.**, New York, NY (US)
(72) Inventor: **Mihir Bhansali**, New York, NY (US)
(73) Assignee: **FIRESTAR DIAMOND, INC.**, New York, NY (US)

(**) Term: **15 Years**

(21) Appl. No.: **29/552,654**

(22) Filed: **Jan. 25, 2016**

(51) **LOC (10) Cl.** **11-01**

(52) **U.S. Cl.** **D11/90**
USPC **D11/90**

(58) **Field of Classification Search**

USPC D11/1-2, 26-29, 89-92; 63/26-28, 32
CPC A44C 17/00
See application file for complete search history.

CLAIM

The ornamental design for a jewel design, as shown and described.

DESCRIPTION

FIG. 1 is a front top perspective view of the present invention.

FIG. 2 is a front elevation view of FIG. 1, the rear elevation view being a mirror image thereof.

FIG. 3 is a right side elevation view of FIG. 1, the left side elevation being a mirror image thereof.

FIG. 4 is a top plan view of FIG. 1; and,

FIG. 5 is a bottom plan view of FIG. 1.

No claim is made to features not shown in the present drawings.

1 Claim, 4 Drawing Sheets
